UNITED STATES PATENT OFFICE.

ROBERT W. KREMER, OF EAST CLEVELAND, OHIO, ASSIGNOR TO CARLYON MANUFACTURING COMPANY, OF EAST CLEVELAND, OHIO.

GREASE-GUN.

1,165,883.

Specification of Letters Patent. Patented Dec. 28, 1915.

Application filed April 2, 1915. Serial No. 18,793.

To all whom it may concern:

Be it known that I, ROBERT W. KREMER, citizen of the United States, residing at East Cleveland, in the county of Cuyahoga and State of Ohio, have invented certain new and useful Improvements in Grease-Guns, of which the following is a specification.

This invention relates to grease guns commonly used for the purpose of forcing a quantity of grease into gear casings, such as an automobile differential or the like.

The object of the invention is to provide an improved grease gun which can be readily charged with the lubricating material, by means of openings in the sides of two telescoping tubes which form the barrel of the device, the construction being such that the tubes can be readily put together or taken apart, or turned to open or close the openings through which the material is introduced.

The invention is illustrated in the accompanying drawings in which,

Figure 1 is a plan view of the device. Fig. 2 is a perspective of one member of the barrel. Fig. 3 is a perspective of the other member. Fig. 4 is a longitudinal section. Fig. 5 is a cross section.

Referring specifically to the drawings, the barrel of the device is composed of two tubular parts, the outer one of which is indicated at 6, and the inner one at 7. The part 6 is split along its entire length as indicated at 8, the edges of the split being spaced apart. This member is fastened at its rear end to and within the flange of a cupped cap 9 having a opening through which works the rod 10 carrying the piston 11. The other tubular member 7 is also split from one end to the other as indicated at 12, the split being widened or enlarged for the greater part of its length as indicated at 13. The front end of this member is fixed in a front cupped cap 14, which has a delivery spout 15 projecting forwardly therefrom. The tube is spaced slightly from the inner surface of the wall or flange of the cap 14, as indicated at 16, this space being wide enough to receive, at a snug fit, the front end of the shell 6.

The caps 9 and 14 are provided with projections 17 which may be grasped to turn the tubes with respect to each other.

When the tubes are telescoped, with the tube 7 within the tube 6, a barrel is formed to contain the grease. By turning the tubes until the openings 8 and 13 register with each other the barrel can be readily filled with the material, and then the tubes are turned half around, whereby the openings are closed and a complete barrel is formed, from which the material may be ejected by pressing the piston 11 forwardly.

The inner tube 7 is so constructed that it expands to tight contact against the outer tube 6. This action is permitted by the split 12 in the tube, and the result is to prevent grease from oozing or leaking around and out between the tubes. When pressure is applied to the piston the inner tube is expanded to close contact with the outer tube, preventing the leakage referred to. The two members of the barrel can be readily pulled apart to remove the piston or for other purposes. Expansion of the outer tube 6 under pressure is prevented by the fact that one end thereof fits snugly within the cap 9 to which it is fastened and the other end thereof fits snugly within the other cap 14, but as stated the inner tube is free to expand slightly to form a tight joint.

What I claim as new is:

A grease gun comprising two end caps, an inner split tube secured to one cap and having an opening in the side thereof, an outer split tube secured at one end to the other cap and fitting at its other end in the first mentioned cap and having a side opening which may be registered with the opening in the inner tube, a spout extending from the first mentioned cap, and a piston in the inner tube having a rod extending through the other cap.

In testimony whereof, I affix my signature in presence of two witnesses.

ROBERT W. KREMER.

Witnesses:

EARL L. KREMER,
